The ornamental design for an analyzer enclosure, as shown and described.

DESCRIPTION

FIG. 1 is a right front top perspective view of an analyzer enclosure showing my new design and showing unclaimed environmental structure in broken lines;

FIG. 2 is a left front top perspective view thereof;

FIG. 3 is front elevation view thereof;

FIG. 4 is rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a right front top perspective view similar to FIG. 1, showing further unclaimed environmental structure in broken lines.

The broken lines in the drawings are for purposes of illustrating portions of the analyzer enclosure as well as additional environmental structures that form no part of the claimed design.
